(57) **CLAIM**

The ornamental design for a nostril hair trimmer, as shown and described.

DESCRIPTION

FIG. 1 is an assembled perspective view of a nostril hair trimmer;

FIG. 2 is a front view thereof;

FIG. 3 is a rear view thereof;

FIG. 4 is a left side view thereof;

FIG. 5 is a right side view thereof;

FIG. 6 is a top view thereof; and

FIG. 7 is a bottom view thereof;

FIG. 8 is perspective view of a base of the nostril hair trimmer;

FIG. 9 is a front view thereof;

FIG. 10 is a rear view thereof;

FIG. 11 is a left side view thereof;

FIG. 12 is a right side view thereof;

FIG. 13 is a top view thereof; and

FIG. 14 is a bottom view thereof;

FIG. 15 is a perspective view of a head of the nostril hair trimmer;

FIG. 16 is a front view thereof;

FIG. 17 is a rear view thereof;

FIG. 18 is a left side view thereof;

FIG. 19 is a right side view thereof;

FIG. 20 is a top view thereof; and

FIG. 21 is a bottom view thereof;

FIG. 22 is a partial enlarged taken from FIG. 8;

FIG. 23 is a partial enlarged taken from FIG. 9;

FIG. 24 is a partial enlarged taken from FIG. 10;

FIG. 25 is a partial enlarged taken from FIG. 11;

FIG. 26 is a partial enlarged taken from FIG. 13; and,

FIG. 27 is a partial enlarged taken from FIG. 15.

The broken lines in the figures depict portions of the nostril hair trimmer that form no part of the claimed design. The base and the head of the nostril hair trimmer are shown separately for convenience of illustration.
